CLAIM

The ornamental design for a golf cart, as shown and described.

DESCRIPTION

FIG. 1 is a perspective view of a golf cart; FIG. 2 is another perspective view thereof; FIG. 3 is a third perspective view thereof; FIG. 4 is a fourth perspective view thereof; FIG. 5 is a front elevation view thereof; FIG. 6 is a rear elevation view thereof; FIG. 7 is a left side elevation view thereof; FIG. 8 is a right side elevation view thereof; FIG. 9 is a top plan view thereof; FIG. 10 is a bottom plan view thereof; FIG. 11 is an enlarged partial view showing a part labeled 11 in FIG. 1; FIG. 12 is an enlarged partial view showing a part labeled 12 in FIG. 1; FIG. 13 is an enlarged partial view showing a part labeled 13 in FIG. 2; FIG. 14 is an enlarged partial view showing a part labeled 14 in FIG. 3; FIG. 15 is an enlarged partial view showing a part labeled 15 in FIG. 3; FIG. 16 is an enlarged partial view showing a part labeled 15 in FIG. 4; and, FIG. 17 is an enlarged partial view showing a part labeled 15 in FIG. 8, showing our new design.

The evenly-spaced broken lines showing portions of the golf cart form no part of the claimed design. The unevenly-spaced broken lines are used to indicate the portions of the features shown enlarged and form no part of the claimed design.
